UNITED STATES PATENT OFFICE.

JAMES DUNCAN, OF COSHOCOTON, OHIO.

SCHOOL SEAT AND DESK.

SPECIFICATION forming part of Letters Patent No. 432,662, dated July 22, 1890.

Application filed May 18, 1888. Serial No. 274,291. (No model.)

To all whom it may concern:

Be it known that I, JAMES DUNCAN, a citizen of the United States, residing at Coshocton, in the county of Coshocton and State of Ohio, have invented certain new and useful Improvements in a Combined School Seat and Desk, of which the following is a specification, reference being had therein to the accompanying drawings.

10 This invention has relation to school seats and desks; and it consists in certain peculiarities in the construction, arrangement, and combination of parts, substantially as will be hereinafter described, and particularly pointed out in the subjoined claims.

15 One object of my invention is to construct a school desk and seat which can be adjusted to suit occupants of different sizes.

Another object of my invention is to construct a school-desk which can be adjusted vertically to such an extent as will permit its being used by a person standing, and one in which the angle of inclination may be changed to suit the user.

25 The objects generally of my invention are to provide a school desk and seat which, by reason of its simplicity of construction, the cheapness with which it can be manufactured, and the many advantages which it possesses, 30 will readily recommend itself to those persons familiar with this class of invention.

In the accompanying drawings, illustrating the invention, and on which the same letters of reference designate the same or corresponding parts, Figure 1 is an end elevation of my improved school desk and seat, showing the same adjusted to their uppermost and lowermost positions in full and broken lines, respectively. Fig. 2 is a side view of a portion of 40 the same, looking at the inside, and shows the means for holding the desk at any desired height. Fig. 3 is a detail view showing the manner of engagement of the adjustable desk and seat-back. Fig. 4 is a rear side view of my improved school desk and seat. Fig. 5 is a detail view of means for connecting the seat and desk-support together. Fig. 6 is a detail view of that portion of said desk-support which includes the field of adjustment of the 45 seat. Fig. 7 is a detail view of a bolt having a peculiarly-shaped head and serving to connect the seat and support together. Fig. 8 is

a view of the desk proper, showing means for securing the arms J thereto. Fig. 9 is a cross-section view of the same. Fig. 10 is a detail view showing a pinion having a toothed collar, forming a part of the means used in the vertical adjustment of the desk proper.

A designates the standards of my improved school desk and seat, of which standards there are obviously two, located one at either side of the same. Secured to each of these standards A and extending across the space between the same is the portion B, which forms the back for the seat and the front for the desk. This portion B may be constructed of a series of slats b, having dovetailed connection, or it may be constructed in any other suitable manner without departing from the spirit of the invention.

Each of the standards A is formed or provided with a projection C, the inner surface of each of which is formed with a dovetailed recess c, (shown best in Fig. 3,) which is engaged by a similarly-shaped projection D, secured to the under side of the desk proper E. This desk E is also provided with depending rack-bars F, the teeth of which engage a toothed collar G, projecting from and preferably formed integral with a pinion G', which is mounted upon a horizontal shaft H, extending from one of the standards A to the other. On reference to Fig. 1 it will be seen that these rack-bars F are of comparatively great length, so that a considerable range of adjustment of the desk E is permitted, whereby the height of said desk can be fixed to suit the requirements of the user. This desk E consists of the parts e and f, the latter of which parts is hinged to the part e, so that its angle of inclination can be changed. To permit this adjustment of the part f the casting D, which is secured to the under side of the portion e of the desk, is formed with a depending portion d, having a lateral perforation, through which passes a thumb-screw or other suitable securing means D', and confined between the head of this thumb-screw D' and the outer surface of the depending portion d of the casting D is the casting l, which is in shape an arc of a circle. This casting is formed with an elongated slot g, and is secured at one of its ends to the under side of the portion f of the desk E, and its

inner surface is formed with teeth g' , of which any desired number may be employed. These teeth g' are adapted to be engaged by the end of a pawl g^2 , which is pivoted to the depending portion d of the casting D, whereby the hinge portion f of the desk E will be rigidly held in any desired position by the engagement of said teeth and pawl.

The desk E is raised and lowered by means 10 of a hand-wheel L, mounted on the shaft H, and it is held in its adjusted position by means of pawls M engaging the pinion G', said pawls being pivoted to the inner side of the standards A, all of which is clearly shown in 15 Fig. 4.

The outer surfaces of the rack-bars F are formed with recesses F', which receive projections F², extending from the inner sides of the standards A, by which means said rack-bars are guided and prevented from wabbling in the adjustment of the desk E, and the recesses c in each of the projections from the standards A and the projections d² from the casting D perform the same purpose for the 25 desk E, forming double parallel guides for the desk E, all of which will be clearly understood.

Secured to the inner side of the portion B of the desk is the receptacle N for the books, 30 slates, and other property of the scholar. In order to gain access to the interior of this receptacle N, said receptacle is provided with a hinged portion N' at its top, and the shaft H, hereinabove referred to, is preferably located 35 immediately above said receptacle N, although it is obvious that in such location I do not limit myself. Each of the standards A is provided near its lower end with a vertical elongated slot O and with notches o, 40 opening into said slot O and located on opposite sides thereof in alignment with each other. The notches o o are arranged like a series of steps, having a substantially horizontal bearing o' each side of the slot and an inclined face o² o², extending down and toward the center of the slot, and also extending obliquely away from the center of the slot in such a manner as to receive and accommodate the bolt-head P, which is made substantially in 45 the shape of a truncated cone and constructed with a horizontal straight flat surface P' on the top and two surfaces beveled in two directions, both inwardly and toward the center and down, and is designated by the reference-letter P². From the peculiar construction of this bolt-head and the notches it will be observed that the lower beveled sides P² P² have a long solid bearing on the beveled edges O² O² of the notches, as shown clearly 55 in Figs. 6 and 7, taken together. The bolt P³ is provided with a nut Q on its inner end, which, when unscrewed, permits of the outward movements of the bolt-head and facilitates the vertical adjustment of the seat R. 60 Secured to the under side of this seat, at opposite sides thereof, is a bracket S, tapered in outline and strongest at the pivotal point of

support T. At this point the seat is provided with a circular bearing which fits with a correspondingly-curved bracket-support w. In front of the pivotal support T is a projecting stop v, which serves to limit the downward movement of the seat and stop it in a substantially horizontal position. The curved arms w are secured in position by the bolts 75 P³ and are secured against dropping forward and letting the seat down by oppositely-projecting lips or flanges v' and v².

It is obvious from the foregoing description, taken in connection with the illustrations, 80 that the seat may be adjusted to any desired elevation and securely held in position to accommodate children of different sizes and ages. Near the front edge of the stationary shelf e is a vertically-projecting strip e', and in front of this strip e' is a receptacle f' to receive and accommodate pens, pencils, eraser, rubbers, &c., and at the rear free edge of the tilting portion f is a second rib f², which extends only part way across the tilting shelf, 85 leaving a clear uninterrupted space for the free and comfortable play of the forearm of the student, said rib serving to retain books, papers, &c., on the desk. Its right-hand end, being smoothly beveled, thus secures the 90 greatest comfort and least obstruction to the movement of the arms of the student in writing.

Having described the objects, uses, and advantages of my device, and having set forth 100 in detail the construction of a desk embodying my invention, what I desire to secure by Letters Patent, and what I therefore claim, is—

1. In a school-desk, the supporting-stands 105 having projections provided with recesses on their inner surfaces, in combination with the desk proper, rack-bars, and projections secured to said desk, forming a double guide, a horizontal shaft having its bearings 110 in said standards, a pinion mounted thereon and having a collar formed with teeth engaging with the teeth of said rack-bars, and a pawl locking the desk in an elevated position, substantially as and for the purposes specified. 115

2. In a school-desk, the supporting-stands 120 having projections provided with recesses on their inner surfaces, in combination with the desk proper, rack-bars, and projections secured to said desk, forming a double guide, a horizontal shaft having its bearings 125 in said standards, a pinion mounted thereon and having a collar formed with teeth engaging with the teeth of said rack-bars, a pawl locking the desk in an elevated position, and a hand-wheel also mounted on said shaft and operating the same to raise and lower said desk, substantially as and for the purposes specified.

3. In a school-desk, the supporting-stands 130 having projections provided with recesses on their inner surfaces, in combination with the desk proper, rack-bars, and projections secured to said desk, forming a double

guide, a horizontal shaft having its bearings in said standards, a pinion mounted thereon and having a collar formed with teeth engaging with the teeth of said rack-bars, and a pawl engaging the pinion and serving to lock the desk in its elevated position.

4. In a school-desk, the combination, with a vertical adjustable desk proper, consisting of a stationary shelf *e* and a hinged shelf *f*, of means for adjusting said desk, castings rigidly secured to said hinged portion *f* and provided with teeth on the top of said castings, and an arc-shaped slot extending along and through said castings, with set-screws for adjusting the hinged portion *f* to any desired angle, and pawls engaging the teeth of said castings, and arms *d*, which support the pawls, as set forth.

5. In a school seat and desk, the combination, with the standards formed with vertical slots and inclined notches, of the seat-support formed with oppositely-projecting flanges *v'*

and *v*², engaging said standards, and provided with a bolt having a polygonal head fitting said notches, and the nut on said bolt.

6. The combination, with the standards formed with horizontal rests, of the desk-supporting frame formed with downwardly-projecting rack-bars passed through said rests, whereby said rests form guides for said rack-bars and stops for the downward movement of the frame, the projections *d*² *d*², forming a double guide, and the pinions beneath said rests and formed with horizontal toothed collars and pawls, all substantially as shown, and for the purposes set forth.

In testimony whereof I affix my signature, in presence of two witnesses, this 9th day of April, 1888.

JAMES DUNCAN.
